CLAIM

The ornamental design for a sensor module holder, as shown and described.

DESCRIPTION

FIG. 1 is a front, top, and right perspective view of a sensor module holder embodying the new design;

FIG. 2 is a rear, bottom, and right perspective view thereof; FIG. 3 is a rear elevational view thereof;

FIG. 4 is a front elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a front, bottom and right perspective view of the sensor module holder, shown in condition of use and coupled with an L-bracket and clip to aid in attachment to an article of clothing; the L-bracket and clip are disclosed in broken lines to illustrate an environment;

FIG. 10 is a rear, bottom, and right perspective view thereof; FIG. 11 is a top plan view thereof;

FIG. 12 is a front elevational view thereof;

FIG. 13 is a front, bottom and right perspective view of the sensor module holder, shown in condition of use and coupled with a clip to aid in attachment to glasses or an article of clothing; the clip is disclosed in broken lines to illustrate an environment;

FIG. 14 is a front elevational view thereof;

FIG. 15 is a right side view of the sensor module holder, shown in condition of use and coupled with an alternate clip to aid in attachment to an article of clothing; the clip is disclosed in broken lines to illustrate an environment;

FIG. 16 is a rear, bottom, and left perspective view thereof; FIG. 17 is a top plan view of the sensor module holder, shown in condition of use and coupled with $\frac{1}{4}$ inch mount to aid in attachment to a stand or other structure; the mount is disclosed in broken lines to illustrate an environment; and, FIG. 18 is a right side view thereof.

The broken lines depict portions of the sensor module holder in which the design is embodied that form no part of the claimed design. The broken lines showing an L-bracket, clip, and mount represent environmental structure and form no part of the claimed design. Additionally, the dash-dot lines denote the boundary of the claim and form no part of the claimed design.
